UNITED STATES PATENT OFFICE.

ARTHUR HAMMERSTEIN, OF NEW YORK, N. Y.

SELF-CLOSING STOPPER FOR RECEPTACLES.

Application filed September 16, 1927. Serial No. 219,834.

The invention relates to receptacles designed to contain fluids and other substances which are expelled in successive amounts at periodic intervals of use, examples of such 5 receptacles being found in the customary containers for perfumes, shaving lotions, creams, tooth washes, powders and pastes, and the like. The object of the invention is to provide a stopper of simple and novel construction, whereby such receptacles will be automatically sealed and whereby discharge of the contents may be brought about at will in a simple manner. The invention will be fully described hereinafter and the features of novelty will be pointed out in the claims.

In the accompanying drawing, which illustrates an example of the invention without defining its limits, Fig. 1 is a sectional elevation of the stopper in position upon a receptacle; Fig. 2 is an inverted plan view of the stopper, and Fig. 3 is a sectional plan view on the line 3—3 of Fig. 1.

The stopper comprises a fitting arranged to be attached to the exit end of a receptacle 25 10, which may be of any suitable form and dimensions, and constructed in any conventional manner of suitable material. In its illustrated form the fitting consists of a closure member 11, detachably connected with the receptacle 10, for instance by being provided with an externally screwthreaded neck 12, arranged to screw into the internally threaded neck 13 of the receptacle 10; to prevent unintentional escape of the contents of the receptacle 10 a packing ring 14 may be located between the member 11 and the receptacle neck 13. The closure member 11 is provided with an outwardly converging recess 15, preferably of conical form, and in any case communicating with the interior of the receptacle 10 as shown in Fig. 1. The closure 11 is further provided exteriorly of the receptacle 10 with a seat 16, preferably of frusto-conical shape, and further includes exit apertures 17 at the seat in communication with the recess 15. The stopper is further provided with an externally screwthreaded boss 18, adapted to removably receive a cap 19 having an interior chamber 20 fitted over the seat 16, as illustrated in Fig. 1; the cap 19 in addition is provided at its outer end with a reduced guidebore 21, which forms an axial continuation of the chamber 20 and slidably accommodates a plunger 22. The latter extends into the chamber 20 and projects outwardly beyond the cap 19 and is provided with an axial exit

passage 23, the inner end of which is normally closed by the outer end surface of the seat 16. At its inner end, the plunger 22 carries a sealing member 24, slidably fitted in the chamber 20 in fluid tight engagement with the surface of said chamber, said sealing member being shaped to fit over and in surface engagement with the aforesaid seat 16 so as to normally close the exit apertures 17 as shown in Fig. 1. An actuating head 25 is mounted upon the plunger 22 at its outer end, preferably so as to be removable, and in the illustrated example, accordingly is shown in screwthreaded engagement with said plunger; the head 25 which virtually forms a part of the plunger 22 is provided with an axial exit passage 23 forming a continuation of the passage 23. In order to automatically maintain the sealing member 24 in surface engagement with the seat 16, and to automatically return it to this position, a spring 26 is located within the chamber 20 between the outer end wall thereof and the sealing member 24, said spring exerting a tension upon said sealing member in a direction toward the seat 16. To facilitate the expulsion of the contents of the receptacle 10, when this is desired, the cap 19 may include an outer surface 19^a shaped or more specifically curved to accommodate the thumb 80 and preferably also the first finger of the hand of the person manipulating the stopper; the head 25 may, if desired, be provided with a cooperating surface 25^a for the accommodation of the end of the thumb as diagrammatically illustrated in Fig. 1.

In practice, with the parts in the normal positions shown in Fig. 1, the receptacle is securely sealed and unintentional discharge of its contents are positively prevented. 95 When it is desired to expel the contents of said receptacle 10, the plunger 22 is moved outwardly with respect to the cap 19 so as to shift the sealing member 24 in a direction away from the seat 16 to thereby uncover the exit apertures 17 and accordingly establish communication between said apertures 17 and the exit passage 23—23^a. In this adjustment of the parts, the contents of the receptacle 10 to any desired amount may be expelled through the aforesaid passage, for instance, in successive squirts, by shaking the receptacle to and fro in an inverted position. The provision of the surface 19^a and if desired, the surface 25^a makes it possible 110 to shift the plunger 22 and sealing member 24 as described, by pressure upon the head

25 through the medium of the thumb, while the receptacle is easily and comfortably grasped by the hand in a natural position. As soon as the outward pressure upon the 5 plunger 22 or more specifically upon the head 25 is released, the spring 26 will immediately return the sealing member 24 into sealing engagement with the seat 16 so as to again cover the exit apertures 17.

10 The stopper may be efficiently utilized in connection with receptacles adapted to contain all sorts of fluids, and particularly perfumes and the like, and may be developed also in a form suitable for receptacles 15 designed to contain granular and pulverized solids, pastes and the like.

The device may be easily and completely disassembled for cleaning or other purposes, by unscrewing the cap 19 from the boss 18 20 and by removing the head 25 from the plunger 23, after which the latter with the sealing member 24 and the spring 25 may be easily removed from said cap 19; reassembling of the parts is equally simple as 25 will be obvious. The stopper is extremely simple in construction and operation, and may be economically produced and easily attached to the receptacle for which it is designed. The elements of the stopper are 30 combined in a manner to prevent unintentional separation thereof and so as to cooperate in an efficient manner to automatically maintain the receptacle normally in a sealed or closed condition. The outwardly diverging and preferably conical form of the recess 35 15 serves to guide or conduct the contents of the receptacle 10 to the exit opening 17 when expulsion of said contents from said receptacle is desired.

40 Various changes in the specific form shown and described may be made within the scope of the claims without departing from the spirit of the invention.

I claim:—

45 1. A stopper of the kind described comprising a fitting arranged to be attached to the exit end of a receptacle in communication with the interior thereof, an apertured seat located in a stationary position within said fitting, and a hollow plunger slidably mounted in said fitting in axial registry with said seat and projecting exteriorly of said fitting, said plunger co-operating with said seat to close said exit end of the receptacle, and being axially movable away from said seat to 50 uncover the apertures thereof and permit the contents of said receptacle to be expelled therethrough and through said hollow plunger.

60 2. A stopper of the kind described comprising a fitting arranged to be attached to the exit end of a receptacle in communication with the interior thereof, an apertured seat located in a stationary position within said fitting, a plunger slidably mounted in said

fitting in axial registry with said seat and provided with an axial exit passage, sealing means carried by said plunger adapted to engage said seat and close the apertures thereof to thereby close the exit end of said receptacle, said plunger being axially movable outwardly in said fitting to uncover said apertures and establish communication between said seat apertures and said axial exit passage to permit the contents of the receptacle to be 70 expelled through said passage, and a spring for maintaining said sealing means in engagement with said seat and for returning it thereto.

3. A stopper of the kind described comprising a fitting arranged to be attached to the exit end of a receptacle in communication with the interior thereof, a frusto-conical seat located in a stationary position within said fitting and provided with exit apertures contiguous to its outer end, a plunger slidably mounted in said fitting in axial registry with said seat and having an axial exit passage, the inner end of which is normally closed by the outer end surface of said seat, a sealing 90 member carried by said plunger and adapted normally to fit over and in surface engagement with said seat to close the apertures thereof, said plunger being axially movable outwardly in said fitting to uncover said apertures and establish communication between said apertures and axial exit passage and thereby permit the contents of the receptacle to be 95 expelled through said passage, and a spring located within said fitting for maintaining said sealing member in surface engagement with said seat and for returning it thereto.

4. A stopper of the kind described, comprising a closure member arranged to be attached to the exit end of a receptacle and provided with an outwardly converging recess communicating with the interior thereof, a frusto-conical seat on said closure member, the latter including exit apertures at said 105 seat in communication with said recess at the apex end thereof, a cap removably secured on said closure member and provided with an interior chamber fitted over said seat and with a reduced guide bore at its outer end 110 forming an axial continuation of said chamber, a plunger slidably mounted in said guide bore and projecting exteriorly of said cap, said plunger being provided with an axial 115 exit passage, the inner end of which is normally closed by the outer end of said seat, a sealing member carried by said plunger and slidably fitting said chamber, said sealing member being shaped to fit over and in surface engagement with said seat to normally 120 close said exit apertures, said plunger being movable outwardly relatively to said cap to shift said sealing member away from said seat and thereby establish communication 125 between said exit apertures and exit pas- 130

sage whereby the contents of said receptacle may be expelled through the latter, and a spring within said chamber for yieldingly maintaining said sealing member in surface engagement with said seat and for returning it thereto.

5. A stopper of the kind described comprising a fitting arranged to be attached to the exit end of a receptacle in communication 10 with the interior thereof, an apertured seat located in a stationary position within said fitting, a hollow plunger slidably mounted in said fitting in axial registry with said seat and projecting exteriorly thereof, said plunger 15 co-operating with said seat to close said

exit end of the receptacle, and being axially movable to uncover the apertures of said seat and permit the contents of said receptacle to be expelled therethrough and through said hollow plunger, and a head on said plunger 20 exteriorly of said fitting for operating said plunger, said fitting having an outer surface curved to accommodate the thumb and permit it to exert an operating pressure on said head whereby the expulsion of said contents 25 is facilitated.

In testimony whereof I have hereunto set my hand.

ARTHUR HAMMERSTEIN.
